COMBINATION INFLATABLE AND HARD SHELTER

Bernard Caminker, Tustin, Calif., assignor to Hughes Aircraft Company, Culver City, Calif., a corporation of Delaware

Filed Oct. 11, 1967, Ser. No. 8,952

Term of patent 14 years

(Cl. D13—1)

Fig. 1.

Fig. 6.

Fig. 2.

Fig. 3.

Fig. 4.

Fig. 5.

FIGURE 1 is a perspective view of a combination inflatable and hard shelter showing the new design;

FIGURE 2 is a rear elevational view thereof, the front elevational view being symmetrically identical;

FIGURE 3 is a plan view thereof;

FIGURE 4 is a left end elevational view thereof;

FIGURE 5 is a right end elevational view thereof;

FIGURE 6 is a bottom view thereof.

I claim:

The ornamental design for a combination inflatable and hard shelter, substantially as shown and described.
